UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

LINOTYPE-MACHINE.

No. 919,024.

Specification of Letters Patent.

Patented April 20, 1909.

Application filed March 24, 1908. Serial No. 422,872.

To all whom it may concern:

Be it known that I, DAVID S. KENNEDY, of the borough of Brooklyn, county of Kings, and State of New York, have invented a new 5 and useful Improvement in Linotype-Machines, of which the following is a specification.

My invention has reference to line-casting machines of the general organization represented in Letters Patent of the United States #436,532, and more particularly to such machines when provided with quadding or paragraphing devices represented in Letters Patent of the United States #786,155. 10 15 In this mechanism, the matrices are assembled in a horizontal line in the top of a so-called assembling elevator, by which the completed line is lifted between two depending fingers on a horizontally movable carriage. 20 The movement of this carriage to the left shifts the composed line to the left out of the elevator, in its path to the casting mechanism. In practice, it is found that the right-hand finger e^2 in Patent #786,155, standing normally above the point at which the matrices enter the line, and serving to push the completed line forward to the left, will, under certain conditions, interfere with the free passage of the matrices and wedge justifiers to their places at the end of the line. 25

The object of my invention is to avoid this interference on the part of the finger, and it consists in combining with the finger, means whereby it is automatically held away from its operative position during the composition of the line.

In the drawing I have shown my device in a preferred form as applied to a machine such as, shown in Patent #786,155, but it 40 is to be understood that the form and arrangement of parts may be modified provided their general mode of action is retained, and it will also be understood that the devices may be applied to all machines of the general 45 character shown.

In the drawing,—Figure 1 is a front elevation of the assembler elevator and attendant parts in accordance with my invention, the finger being raised to its inoperative position. Fig. 2 is a similar view with the finger in the active position which it assumes after the completion of the line. Fig. 3 is a perspective view showing the finger and its controlling device.

Referring to the drawings, A represents the 55 inclined constantly running belt upon which the matrices B are delivered in succession from the magazines as the finger-keys are operated, and from which they are delivered over an inclined supporting surface C into 60 the horizontal channel in the top of the assembler elevator D in front of the rotary star-wheel E, by which the line is forced endwise to make room for the incoming matrices. 65

F is a horizontally movable transfer carriage, having at the right end the depending finger e^2 mounted on a horizontal pivot e^3 . This finger corresponds with the finger indicated by like letter in Patent #786,155. 70

When the composition of the line is completed, this finger hangs vertically in the position shown in Fig. 2, so that when the matrix line is lifted by the elevator D, it will be embraced between finger e^2 on the right, and 75 the usual corresponding finger, not shown, at the left end of the carriage F. If the finger is permitted to remain in the position shown in Fig. 2 during the composition of the line, its lower end will occasionally interfere somewhat with the downward passage of the matrices and the wedge spacers, which are delivered as usual from their magazine. 80

So far as described, the parts are or may be 85 of the ordinary construction.

In applying my improvement, having in view the automatic movement of the finger to and from its operative position, I mount on the front of the frame a vertically sliding bar G, urged constantly upward by a spring H, and provided near its upper end with a lip g to act against the finger, and at its lower end with a lip g' , engaging beneath the assembling elevator D. 90

When the elevator is down in the normal 95 or assembling position, it holds the slide G down in the position shown in Figs. 1 and 3, so that the lip g bears against a shoulder on the finger e^2 and holds the latter upward to the left of the assembling position and away 100 from the path of the ingoing matrices and spacers. The finger is thus prevented from interfering with the composition and is also kept out of the way so that the operator may have free access to the assembler for the purpose of removing, inserting, or rearranging matrices as is frequently necessary. 105

When the composition of the line is com-

pleted and the elevator D raised, the slide G is released and permitted to move upward, disengaging its shoulder g from the finger e^2 and permitting the latter to fall to the position shown in Fig. 2. This position is assumed instantly so that as the assembler continues upward with the matrix line, the line is carried against the left face of the finger e^2 , by which it is confined and moved to the left when the carriage F is shifted, after the elevator completes its upward motion. The assembling elevator is immediately lowered to its normal position, thereby depressing the lip g of the slide to its first position, shown in Fig. 1. While the lip is in this position, the carriage returns from the left to its normal position, shown in Fig. 1, carrying with it the finger e^2 , which is encountered by the lip g and compelled to swing upward to the position shown in Fig. 1, as the carriage completes its movement. This movement is due, of course, to the fact that the shoulder on the finger bears against the lip g , while the pivot of the finger continues to move to the right with the carriage F.

From the foregoing, it will be understood that the finger is held normally out of action, or away from the assembling point; it is automatically dropped to the vertical or operative position as the elevator begins its ascent; and that it is automatically lifted to and sustained in the inoperative position as the carriage returns to its normal position. This finger e^2 is commonly known in the art as the right-hand line-shifting finger.

I believe it to be wholly new in the art to combine with the line-shifting carriage and a finger movably attached thereto, means for holding the finger away from the composing point during composition. I also believe it to be wholly new to combine with the finger as stated, means for effecting its movement to and from the operative position automatically.

Having thus described my invention, I

claim and desire to secure by Letters Patent,—

1. In a machine of the class described, a line-shifting carriage provided with a pivoted finger, and automatic means for moving the finger away from the assembling point when the carriage assumes its normal position.

2. In a machine of the class described, a horizontally movable line-shifting carriage F provided with the pivoted finger e^2 , in combination with a movable stop to lift and sustain the finger as the carriage assumes its normal position.

3. In a machine of the class described, an assembling elevator wherein the matrix line is composed, a horizontally movable carriage provided with a pivoted finger to shift the line from the elevator, and means controlled by the elevator for determining the position of the finger with reference to the assembling point.

4. In combination with the assembler elevator D, the line-shifting carriage F and the finger e^2 pivoted to the carriage, the spring-actuated slide G controlled by the elevator and controlling the position of the finger.

5. In a machine of the class described, a line-shifting carriage provided with a pivoted finger, the assembling elevator, and intermediate means through which the elevator controls the position of the finger.

6. In a machine of the class described, a line-shifting carriage provided with a finger pivoted to move in the direction in which the carriage travels, in combination with the assembling elevator, and means controlled by the elevator to determine the position of the finger.

In testimony whereof I hereunto set my hand this ninth day of March, 1908, in the presence of two attesting witnesses.

DAVID S. KENNEDY.
